FASTENING-INSERTING MACHINE

John F. Standish, Winthrop, Mass., assignor to
United Shoe Machinery Corporation, Paterson,
N. J., a corporation of New Jersey

Application November 13, 1933, Serial No. 697,781

30 Claims.

(Cl. 1—32)

My invention relates to machines by which nails or other fastenings are inserted in the work, it being herein disclosed in connection with apparatus for attaching heels to shoes by nails driven 5 from within said shoes.

An object of this invention is to effect the secure retention of the work upon its support during the driving of the fastenings, this being by relatively simple means not subject to change 10 of the retaining action in use. The transmission of work-clamping pressure through a hydraulic connecting device I have found to best meet these requirements, and I interpose between movable pressing means contacting with the work and movable actuating means therefor, a liquid-containing cylinder movable with one of said means, and a piston operating in the cylinder and movable with the other means, while a valve carried by a mounting held against movement during the 15 normal operation of the machine controls the operating relation between the cylinder and piston, as by governing the flow of the liquid through a passage in the piston. While the valve is open, the work-contacting means may be moved by the operator independently of the actuating means. By closure of the valve, the cylinder and piston will be locked together by a substantially non-compressible agent to communicate pressure from the actuating means to the work-contacting 20 means. Because of the freedom of the valve-mounting from normal movement, its position may readily be varied to permit change in the time of closure of the valve in the operating cycle and therefore the amount of pressure applied to 25 the work. The valve is shown as yieldable upon its mounting to allow movement of the associated elements of the connecting device if the valve has closed the passage. While I have herein shown the cylinder more directly connected to 30 the work-clamping means and the piston under the influence of the actuating means, it is to be understood that this relation may be reversed without departing from the spirit of my invention. In the preferred form of the invention, 35 the frame of the machine, upon which is mounted a work-supporting jack, is provided with vertical ways in which a slide is movable and carries both a pressure-abutment co-operating with the jack and the cylinder of the connecting device. The 40 piston of the connecting device is movable in the cylinder and is provided with a passage, the flow through which is governed by the valve. Preferably, the piston is mounted upon a second slide guided in the ways, and the valve is carried 45 by a support fixed to the frame. As illustrated, a spring elevates each slide and there is also a spring interposed between the support and valve. This valve in the present instance has a stem, and the support for the stem is normally fixed 50 against rotation upon the machine-frame, the

valve spring being interposed between the valve-stem and the support. The support is preferably furnished by a sleeve threaded externally and engaged by a nut movable upon the frame. Rotation of the nut alters the normal position of 5 the valve, as will also rotation of the sleeve. Regardless of the specific construction of the valve and its co-operating elements, I preferably furnish a member movable to adjust the normal position of said valve and means for adjusting the 10 valve independently of the positioning member. By the member, the valve may be caused to assume positions between definite extremes, while the independent movement of the valve may change such extremes simultaneously. There is 15 thus furnished a normal range of adjustment which will lead to the application to the work of pressure between a minimum and a maximum, and if this causes operating troubles both limits may be changed to the same extent. 20

A further object of the invention is to reduce the shock of stopping the pressure-abutment when it is withdrawn from the work. This I effect by means so located that it will not be liable to mutilation by fastenings and the like 25 gathering upon it, which means is preferably variable in position to determine the extent of withdrawing movement of the abutment.

In the accompanying drawings,

Fig. 1 illustrates my invention in partial broken 30 side-elevation as applied to a heel-attaching machine;

Fig. 2 is a section on the line II—II of Fig. 1;

Fig. 3, a front elevation of the jack and nail-ing mechanism; 35

Fig. 4, a section on the line IV—IV of Fig. 2; and

Fig. 5, an enlarged sectional detail on the line V—V of Fig. 2. 40

At the front of a column 10, which furnishes 40 the chief portion of the frame in the illustrated machine, is mounted upon a bracket 12 a jack-post 14. Within the jack a plunger 16 is ar-ranged to reciprocate, this plunger carrying up-wardly extending drivers 18 for nails or other fas-45 tenings, which are supported for insertion upon the upper extremities of the drivers within open-ings in the jack-top. The plunger may be ele-vated for the insertion of the nails by a cam 20 50 contacting with a roll 22 movable upon the lower extremity of said plunger. The cam is fast upon the forward end of a shaft 24 journaled hori-zontally in the frame and receiving power through gearing 26. A spring 28, inserted between a block 30 55 surrounding and bearing upon the shaft and a downward extension 32 of the plunger, serves to lower said plunger and the drivers. The block is retained against displacement along the shaft by the cam on one side, and on the other side by a washer and a screw 33 threaded into the 60

forward end of the shaft. The spring is preferably seated in a cup 34, which is, in effect, a portion of the plunger-extension. This cup, however, is preferably threaded upon a lower cylindrical end 36 of the extension, so by turning it up or down the force exerted by the spring may be varied. The cup is divided vertically to enable it to be locked in its adjusted position by a clamping screw 38. Engagement between the block 30 and the plunger-extension both prevents rotation of the block and guides the plunger.

In the frame are parallel vertical ways 40, 40 in which a slide 42 is arranged to move. At 44 the slide extends over the jack 14 and carries a pressure-head or abutment 46 provided with members 48, which contact with a heel upon the heel-seat of a jacked shoe to retain said heel in place while the attaching nails are being driven. The head is held normally raised, to permit the jacking of the work, by a tension-spring 50 attached at its lower extremity to the frame and at its upper to a lever 52 fulcrumed upon the frame and pivoted at 53 to the slide 42. The extent of upward movement of the head may be adjustably limited by a bumper, the movable element of which is furnished by a threaded rod 54 passing loosely through a vertical opening in a projection 56 from the top of the slide 42 and supported by a nut 58 carried by the threaded portion and resting upon the upper face of the projection. The rod extends down through an opening in a projection 62 from the frame and has a head 60 between which and the bottom of said projection are interposed washers 64, of leather or other yieldable material, which cushion the shock as the spring 50 elevates the slide and head. The point at which the head stops may be determined by varying the position of the nut 58 upon the rod. It will be seen that this bumper is removed from all operating elements, being so situated that nails can not gather upon the cushion to cause it to be cut and thus destroyed. The members 48 are brought into preliminary or measuring contact with the work as the result of the depression of a treadle 66 by the operator. This action is caused to lower the slide and head through a rod 68 joining the treadle to the slide. Engagement of the members 48 with the work having been established, final clamping pressure is to be applied in preparation for the driving of the attaching nails.

Joining opposite sides of the slide 42 at its lower portion is a rearwardly extending reinforcing yoke 70, and opposite the yoke rods 72 secure to the slide a vertical cylinder 74. This cylinder is closed at its lower end and at its upper is open to admit a tubular piston 76. The piston depends from a slide 78 located at the rear of the cylinder, between it and the yoke 70, and guided for vertical movement by projections 80 entering the ways 40. The contact of the piston with the interior of the cylinder may be depended upon to guide the upper portion of the slide 78. An extension 82 of this slide surrounds the shaft 24 and within this extension is retained a block 84 bearing upon the shaft. A compression-spring 86, interposed between the block and a projection 88 from the slide 78, urges the piston up and maintains contact of a roll 90 rotatable upon the bottom of the extension 82 with a cam 92 fast upon the shaft 24, this cam being the element which actuates the slide 42 to place clamping pressure upon the work. The piston, it will be noted, is yieldably supported upon the shaft 24.

Contained in the cylinder and in the tubular piston is such a liquid as oil, indicated at L in Fig. 1 of the drawings. With the lower end of the piston open there may be relative movement between said cylinder and piston, so the operator may freely lower the head 46 by the treadle-rod 68 to produce contact of the members 48 with the work. If the piston-opening be closed, the retention of the substantially incompressible liquid against flow locks the cylinder and piston together, so the effect of the cam 92 may be communicated through these elements to the head to clamp the work upon the jack for the driving of the nails. The control for this purpose is best obtained in the following manner. Across the front of the frame 10, just above the cylinder, is secured a bridge-bar 100 upon the upper face of which a nut 102 (Fig. 5) is mounted to turn. It is shown as held seated in a recess in the bar by a plate 104 attached to said bar by screws 106, 106, separated from each other transversely of the frame near the front of the bar. To facilitate the turning of the nut, a finger-piece 108 extends forwardly therefrom, contact of this finger-piece with the spaced heads of the screws 106 definitely limiting the extent of angular movement. To hold the nut temporarily in the position which it may be turned by the operator, a spring-detent 110 engages a toothed surface of the rear of the nut. The thread of the nut receives the threaded exterior of a sleeve 112, which is allowed to move vertically, but is held against rotation by a projecting finger 113 split and clamped upon the sleeve by a screw 114 (Fig. 2) and extending into a vertical groove 116 in the bar 100. Passing through the sleeve is a rod 118 carrying upon its lower extremity, within the cylinder 74, a ball-valve 120 co-operating with a seat about the open end of the piston 76. Surrounding the rod 118 and located in a counterbore in the sleeve 112 is a spring 122, seated at its lower end upon the bottom of the counterbore and acting at its upper end against a nut and check-nut 124 threaded upon the upper extremity of the rod. The spring holds the ball 120 normally raised but capable of being lowered by engagement of the piston with it. Upward movement of the valve is limited by contact with a circular plate 126 resting upon a shoulder 128 on the rod and forced by the spring 122 against the end of the sleeve. The plate acts as a baffle to prevent the oil from being thrown out of the opening at the upper portion of the piston. Rotation of the nut 102 by its finger-piece will, because of the threaded engagement, raise or lower the sleeve 112 and correspondingly alter the initial separation between the valve and its seat upon the piston. This will, between limits fixed by contact of the finger-piece with the screws 106, change the time in the cycle at which the cylinder and piston are locked together, and the degree of final pressure applied to the work. By loosening the clamping screw 114 the sleeve may be freed from the finger 113 and raised or lowered, with the valve, while the nut remains at rest. By this means the entire range of valve-adjustment may be increased or decreased, the finger being again fixed upon the sleeve after the desired change has been made.

To produce an operating cycle of the machine, power is applied to the shaft 24 through the gearing 26 and a single-rotation clutch governed by a connection at 132 to the rear of the treadle 66. This connection furnishes the fulcrum about which the treadle is lowered during the application of preliminary pressure through the rod 68.

The fulcrum is transferred to the articulation between this rod and the treadle, after the members 48 have contacted with the jacked work and resistance to elevation of the connection 132 by a 5 spring 134 is overcome.

Considering the general operation of the machine, the elements at the beginning of a cycle are related as illustrated in Fig. 1, the drivers 18 being lowered by the spring 28 and the head 46 10 and cylinder 74 elevated by the spring 50. The piston 76 and the ball-valve 120 are also held normally at their highest points by the springs 86 and 122, respectively, they being so positioned that the passage through the piston is open. The operator places nails N, points up, in the driver-passages, jacks a shoe S and applies a heel H to its heel-seat; he then depresses the treadle 66, and through the rod 68 lowers the slide 42 and head 46 to bring the members 48 into engagement with the heel. The cylinder descends with the slide, the contained liquid flowing past the open valve. Having assured himself that the work is correctly placed, the operator continues the depression of the treadle. The transfer of the 15 fulcrum-point trips the clutch through the connection 132, and the power-operation of the machine begins. The cam 92 quickly lowers the slide 78 and the piston 76 until the opening through the latter is closed by the waiting valve 120. Since the liquid can not any longer pass between the piston and cylinder, these are compelled to travel down together under the influence of the cam 92, the spring 122 yielding so the piston may 20 carry the ball with it. The slide 42 and head 46 therefor descend and apply clamping pressure to the work to a degree determined by the contour of the cam 92. The plunger 16 and the drivers 18 are then elevated by the cam 20, and the nails inserted through the heel-seat of the shoe into the heel to effect the attachment. The cycle is 25 completed by the return of all the elements to their initial positions by their springs as permitted by the cams, and the heeled shoe may be removed from the jack. If it is found that the final or machine-pressure is insufficient to 30 hold the work against the displacing force of the drivers, the initial position of the valve 120 may be very conveniently altered by anticlockwise rotation, as viewed from above, of the nut 102 through the finger-piece 108, it being raised so the piston-passage will be closed earlier in the cycle. On the other hand, if the pressure is excessive, tending to break heels or to deform their 35 covering, the nut is rotated in the opposite direction to lower the valve, causing its closure later in the cycle. There is thus introduced more or less lost motion before the locking of the cylinder and piston together occurs to begin the application of final pressure. Some operators may 40 tend to err in one direction or the other, tending to produce either a gapping crease or splitting heels. In this case, the entire range of adjustment by the finger-piece 108 may be altered to prevent such defects. In the first instance, the sleeve 112 is raised to bring the valve closer to the piston and in the second it will be lowered therefrom, in each case the maximum and minimum pressure being changed correspondingly. This may be done by a service-man through 45 adjustment of the sleeve.

Having described my invention, what I claim as new and desire to secure by Letters Patent of the United States is:

1. In a fastening-inserting machine, movable work-pressing means, movable actuating means

therefor, a liquid-containing cylinder movable with one of said means, a piston operating in the cylinder and movable with the other means, a valve for controlling the operating relation between the cylinder and piston, and a mounting 5 for said valve held against movement during the normal operation of the machine.

2. In a fastening-inserting machine, movable work-pressing means, movable actuating means therefor, a liquid-containing cylinder movable 10 with one of said means, a piston operating in the cylinder and movable with the other means, a valve for controlling the operating relation between the cylinder and piston, a mounting for said valve held against movement during the normal operation of the machine, and means arranged 15 to vary the position of the valve upon the mounting.

3. In a fastening-inserting machine, movable work-pressing means, movable actuating means 20 therefor, a liquid-containing cylinder movable with one of said means, a piston operating in the cylinder and movable with the other means, there being a passage in the piston through which the liquid may flow, a valve for controlling the 25 flow of liquid through the passage, a mounting for said valve held against movement during the normal operation of the machine, means arranged to vary the position of the valve upon the 30 mounting, and means arranged to vary the position of the mounting.

4. In a fastening-inserting machine, movable work-pressing means, movable actuating means therefor, a liquid-containing cylinder movable 35 with one of said means, a piston operating in the cylinder and movable with the other means, there being a passage in the piston through which the liquid may flow, a valve for controlling the flow of liquid through the passage, a mounting for said valve held against movement during the normal 40 operation of the machine, and means permitting the valve to yield upon its mounting during such operation.

5. In a fastening-inserting machine, movable work-pressing means, movable actuating means 45 therefor, a liquid-containing cylinder movable with one of said means, a piston operating in the cylinder and movable with the other means, there being a passage in the piston through which the liquid may flow, a valve for controlling the flow 50 of liquid through the passage, a mounting for said valve held against movement during the normal operation of the machine, means arranged to vary the position of the valve upon the mounting, and yieldable means interposed between the valve and 55 the position-varying means.

6. In combination, a frame provided with spaced vertical ways, a work-supporting jack mounted upon the frame, a slide guided in the ways, a work-pressing abutment carried by the 60 slide, a cylinder mounted upon the slide between the ways at the rear of the jack, a piston movable in the cylinder and provided with a passage, a valve for controlling the passage, and means for moving the cylinder and piston. 65

7. In combination, a frame provided with spaced vertical ways, a work-supporting jack mounted upon the frame, a slide guided in the ways, a work-pressing abutment carried by the slide, a cylinder mounted upon the slide, a second slide guided in the ways, a piston mounted upon the second slide and extending into the cylinder, said piston being provided with a passage, a valve for controlling the passage, and means for moving the cylinder and piston together. 75

8. In combination, a frame provided with spaced vertical ways, a work-supporting jack mounted upon the frame, a slide guided in the ways, a work-pressing abutment carried by the slide, a cylinder mounted upon the slide, a second slide guided in the ways, a piston mounted upon the second slide and extending into the cylinder, said piston being provided with a passage, a support fixed to the frame, a valve mounted upon the support to control the passage, and means for moving the piston.
9. In combination, a frame provided with spaced vertical ways, a work-supporting jack mounted upon the frame, a slide guided in the ways, a work-pressing abutment carried by the slide, a cylinder mounted upon the slide between the ways at the rear of the jack, a second slide guided in the ways, a piston mounted upon the second slide and extending into the cylinder, said piston being provided with a passage, a valve for controlling the flow through the passage, and means for moving one of the slides, said moving means also supporting the slide.
10. In combination, a frame provided with spaced vertical ways, a work-supporting jack mounted upon the frame, a slide guided in the ways, a work-pressing abutment carried by the slide, a cylinder mounted upon the slide between the ways at the rear of the jack, a second slide guided in the ways, a piston mounted upon the second slide and extending into the cylinder, said piston being provided with a passage, a valve for controlling the flow through the passage, a spring for elevating each slide, and means for moving one of the slides.
11. In combination, a frame provided with spaced vertical ways, a work-supporting jack mounted upon the frame, a slide guided in the ways, a work-pressing abutment carried by the slide, a cylinder mounted upon the slide between the ways at the rear of the jack, a second slide guided in the ways, a piston mounted upon the second slide and extending into the cylinder, said piston being provided with a passage, a support fixed to the frame, a valve mounted upon the support to control the passage, a spring interposed between the support and valve, and means for moving the piston.
12. In combination, a frame, a work-pressing abutment movable thereon, a cylinder connected to the abutment, an actuating shaft rotatable in the frame, a member bearing upon the shaft, and a piston movable by the shaft and supported by the member.
13. In combination, a frame, a work-pressing abutment movable thereon, a cylinder connected to the abutment, an actuating shaft rotatable in the frame, a member bearing upon the shaft, a piston movable by the shaft, and a spring supported by the member and acting upon the piston.
14. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear of the jack and being closed at the bottom, a second slide movable in the ways and extending above the cylinder, a tubular piston depending from the second slide into the cylinder, a valve controlling the passage through the piston, and a cam rotatable by the shaft and acting upon the piston-slide.
15. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear of the jack and being closed at the bottom, a second slide movable in the ways and extending above the cylinder, a tubular piston depending from the second slide into the cylinder, a bridge extending between the ways, a valve controlling the passage through the piston and having a stem extending above the bridge, means co-operating with the stem for supporting the valve upon the bridge, and a cam rotatable by the shaft and acting upon the piston-slide.
16. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear of the jack and being closed at the bottom, a second slide movable in the ways and extending above the cylinder, a tubular piston depending from the second slide into the cylinder, a bridge extending between the ways, a valve controlling the passage through the piston and having a stem extending above the bridge, means including a spring co-operating with the stem for supporting the valve upon the bridge, and a cam rotatable by the shaft and acting upon the piston-slide.
17. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear of the jack and being closed at the bottom, a second slide movable in the ways and extending above the cylinder, a tubular piston depending from the second slide into the cylinder, a bridge extending between the ways, a valve controlling the passage through the piston and having a stem extending above the bridge, means cooperating with the stem for supporting the valve upon the bridge, means arranged to raise and lower the supporting means, and a cam rotatable by the shaft and acting upon the piston-slide.
18. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear of the jack and being closed at the bottom, a second slide movable in the ways and extending above the cylinder, a tubular piston depending from the second slide into the cylinder, a valve controlling the passage through the piston, a cam rotatable by the shaft and acting upon the piston-slide, and a block bearing upon the shaft and by which the piston-slide is supported.
19. In a heel-attaching machine, a frame pro-

- vided with spaced vertical ways, a jack rising therefrom, nail-drivers operating in the jack, a shaft journaled horizontally in the frame, means carried by the shaft for actuating the drivers, 5 a slide movable in the ways, a pressure-head carried by the slide and co-operating with the jack, a cylinder mounted upon the slide at the rear of the jack and being closed at the bottom, a second slide movable in the ways and extending 10 above the cylinder, a tubular piston depending from the second slide into the cylinder, a valve controlling the passage through the piston, a cam rotatable by the shaft and acting upon the piston-slide, a block bearing upon the shaft and by which 15 the piston-slide is supported, and a spring interposed between the block and piston-slide.
20. In a heel-attaching machine, a frame provided with spaced vertical ways, a jack rising therefrom, nail-drivers operating in the jack, a shaft journaled horizontally in the frame, means carried by the shaft for actuating the drivers, a slide movable in the ways, a pressure-head carried by the slide and co-operating with the jack, a cylinder mounted upon the slide at the rear 25 of the jack and being closed at the bottom, a second slide movable in the ways and extending above the cylinder, a tubular piston depending from the second slide into the cylinder, a valve controlling the passage through the piston, a cam 30 rotatable by the shaft, a roll rotatable on the piston-slide and contacting with the under side of the cam, a block surrounding the shaft, and a spring contacting with the block and piston-slide above the shaft.
35. 21. In a fastening-inserting machine, a movable work-pressing member, actuating means therefor, connections including an hydraulic device between the pressing member and its actuating means, said hydraulic device being provided 40 with a valve, a member movable to adjust the normal position of the valve, and means for adjusting the normal position of the valve independently of such positioning member and prior to the operation of the machine.
45. 22. In a fastening-inserting machine, a movable work-pressing member, actuating means therefor, connections including an hydraulic device between the pressing member and its actuating means, said hydraulic device being provided 50 with a valve, a member movable to change the normal position of the valve between definite extremes, and means arranged to move the valve to change such extreme positions simultaneously.
55. 23. In a fastening-inserting machine, a frame, a work-pressing member movable thereon, actuating means for the work-pressing member, connections including an hydraulic device between the pressing member and its actuating means, said hydraulic device being provided with a valve 60 having a stem, and a support for the valve-stem fixed upon the frame against movement by elements of the machine.
65. 24. In a fastening-inserting machine, a frame, a work-pressing member movable thereon, actuating means for the work-pressing member, connections including an hydraulic device between the pressing member and its actuating means, said hydraulic device being provided with a valve 70 having a stem, a support for the valve-stem fixed upon the frame against movement by elements of

the machine, and a spring interposed between the valve-stem and support.

25. In a fastening-inserting machine, a frame, a work-pressing member movable thereon, actuating means for the work-pressing member, connections including an hydraulic device between the pressing member and its actuating means, said hydraulic device being provided with a valve having a stem, a sleeve surrounding and supporting the valve-stem, and means arranged to hold the sleeve in different positions upon the frame. 10

26. In a fastening-inserting machine, a frame, a work-pressing member movable thereon, actuating means for the work-pressing member, connections including an hydraulic device between the pressing member and its actuating means, said hydraulic device being provided with a valve having a stem, a sleeve surrounding and supporting the valve-stem, means arranged to hold 15 the sleeve in different positions upon the frame, and a spring interposed between the valve-stem and the sleeve. 20

27. In a fastening-inserting machine, a frame, a work-pressing member movable thereon, actuating means for the work-pressing member, connections including an hydraulic device between the pressing member and its actuating means, said hydraulic device being provided with a valve having a stem, an externally threaded sleeve surrounding and supporting the valve-stem, and a nut movable upon the frame and engaging the 25 sleeve-thread. 30

28. In a fastening-inserting machine, a frame, a work-pressing member movable thereon, actuating means for the work-pressing member, connections including an hydraulic device between the pressing member and its actuating means, said hydraulic device being provided with a valve having a stem, an externally threaded sleeve surrounding and supporting the valve-stem, and a clamping member secured to the sleeve and engaging the frame to prevent rotation of said sleeve while permitting longitudinal movement, the clamping member when free allowing the 40 sleeve to be rotated in the nut to assume different vertical positions. 45

29. In a fastening-inserting machine, a frame provided with an opening, a jack having fastening-driving mechanism supported on the frame, 50 a slide movable upon the frame and extending above the jack, said slide having an opening, a pressure-head movable by the slide toward and from the jack, means for elevating the slide and head, a rod extending through the openings, and a cushion interposed between the rod and the frame above a fastening-inserting mechanism. 55

30. In a fastening-inserting machine, a frame provided with an opening, a jack having fastening-driving mechanism supported on the frame, a slide movable upon the frame and extending above the jack, said slide having an opening, a pressure-head movable by the slide toward and from the jack, means for elevating the slide and head, a rod extending through the openings, a cushion interposed between the rod and the frame above a fastening-inserting mechanism, and means arranged to change the vertical position of the rod in the slide-opening. 60 65

JOHN F. STANDISH. 70
